SKI BINDING

Ludwig A. Majneri, Grosse Pointe, Mich.

Application February 16, 1948, Serial No. 8,537

2 Claims. (Cl. 280—11.35)

1

This invention relates generally to ski bindings and refers more particularly to improvements in bindings of the type having provision for clamping the toe as well as the heel portion of a boot on a ski.

Ski bindings of the above general type are usually designed to firmly hold a boot on a ski against movement either transversely or longitudinally of the ski, and are ordinarily equipped with means for yieldably resisting upward movement of the heel portion of the boot relative to the ski. More particularly ski bindings are usually equipped with laterally spaced toe irons respectively engageable with opposite sides of the toe portion of a boot to position the latter on the ski and are provided with some means for positively holding the toe portion downwardly against the ski. Rearward displacement of the boot relative to the toe irons is ordinarily prevented by a cable suitably attached to the ski in advance of the boot and embodying a resilient element which is adapted to be looped around the back of the heel on the boot. The cable is attached so that the resilient element applies a downward thrust on the heel portion relative to the ski and provision is also made for adjusting the tension of the element to vary the extent of downward force applied to the heel portion.

While bindings of the above design have achieved considerable recognition because they actually do firmly hold the boots in place on the skis, nevertheless, they are the direct cause of many leg injuries, especially when used by novices or relatively inexperienced skiers. There are two principal causes of leg injuries or breakage. Briefly, under certain conditions of skiing, an abnormal side strain may be applied to one or both legs of the skier which may be of sufficient magnitude to break either or both legs. Moreover, in skiing under certain conditions, the forward motion of the skis may be impeded or stopped altogether. As a result the skier tends to fall forward, and in so doing, a substantial lifting force is applied to the heel portions of the boots. This lifting force is counteracted by the hold-down cable and may reach such proportions that one or both legs of the skier are strained to the breaking point.

The possibilities of undue leg strain caused by the application of side thrusts is greatly reduced by providing toe irons of the type shown in my copending application, Serial No. 787,808, filed November 24, 1947, now Patent No. 2,517,795, dated August 8, 1950 which automatically release the toe portion of the boot in response to the ap-

2

plication of a laterally outward force on one or both toe irons of a magnitude less than any force capable of unduly straining either or both legs of the skier.

With the foregoing in view, it is an object of this invention to provide a ski binding having means for releasing the heel portion of the boot in response to the application of a lifting force on the boot which is less than any force capable of straining the legs of the skier to the breaking point.

Another object of this invention is to provide a ski binding with a heel releasing device which operates independently of the toe irons and may be employed on bindings having orthodox rigid toe irons, if desired.

A further feature of this invention is to provide a ski binding with a heel release which will release the heel portion of the boot upon the application of a force determined by the tension of the adjustable hold-down device and which is in itself adjustable to permit varying degrees of lifting movement of the heel portion before releasing the latter.

A still further object of this invention is to provide heel releasing means which also assists in positioning the boot in operative relation to the binding.

The foregoing as well as other objects will be made more apparent as this description proceeds, especially when considered in connection with the accompanying drawings, wherein:

Figure 1 is a side elevational view of a ski showing a boot held in position thereon by a binding;

Figure 2 is a plan view of a part of the binding shown in Figure 1 and having certain parts broken away;

Figure 3 is a sectional view taken on the plane 3—3 of Figure 2;

Figure 4 is a cross sectional view taken on the line 4—4 of Figure 3;

Figure 5 is a cross sectional view taken on the line 5—5 of Figure 2;

Figure 6 is a fragmentary plan view of the rear end portion of the binding;

Figure 7 is a side elevational view of the construction shown in Figure 6;

Figure 8 is a cross sectional view taken on the line 8—8 of Figure 7;

Figure 9 is a longitudinal sectional view of a modified form of heel release;

Figure 10 is a sectional view taken on the line 10—10 of Figure 9;

Figure 11 is a sectional view taken on the line 11-11 of Figure 10;

Figure 12 is a sectional view taken on the line 12-12 of Figure 9;

Figure 13 is a longitudinal sectional view of still another form of heel release;

Figure 14 is a sectional view taken on the line 14-14 of Figure 13; and

Figure 15 is a fragmentary plan view of a part of the release shown in Figure 13.

Referring now more in detail to the drawings, it will be noted that the reference character 10 designates a conventional ski and the numeral 11 indicates generally a binding for securing an orthodox ski boot 12 to the ski. The binding 11 comprises a supporting member or base plate 13 attachable to the ski in the usual manner by suitable fastener elements and adapted to form a bearing surface for the heel portion of the boot 12.

In accordance with orthodox practice, the toe portion of the boot 12 is clamped in place on the ski 10 by a pair of toe irons in the form of elongated plates 14, respectively carried by a toe plate 15 shown in Figure 3 of the drawings as secured to the ski at the front end of the plate 13. Referring now to Figure 2 of the drawings, it will be noted that the toe irons converge from the rear end of the toe plate, and are inclined laterally inwardly with respect to the opposite sides of the boot to actually wedge the toe portion of the boot in position on the ski.

In many instances it is desirable to provide a construction which enables adjusting the angle of convergence of the toe irons to compensate for different types of boots, and to assure properly clamping a particular boot in place. One construction used in the past for accomplishing the above result is to provide laterally inwardly extending flanges 16 at the bottom edge of each toe iron. These flanges are slidably supported on the toe plate 15, and are normally concealed by a cover plate 17 suitably secured in place by fastener elements in the form of screws 18. Certain of the screws 18 pass through elongated slots 19 formed in the flanges 16 to enable the unobstructed pivotal movement of the flanges 16 required to adjust the angular relation of the toe irons relative to the boot. The desired adjustment of the toe irons is effected by suitable screws 20 arranged in pairs with one pair associated with each flange 16. As shown in Figure 2 of the drawings, the screws 20 of each pair are respectively positioned at opposite ends of the associated flange 16, and the heads of the two pairs of screws are respectively accessible for manipulation from opposite sides of the binding. Each screw 20 is formed with an enlarged annular portion 21 having the top part extending into a suitable slot 22 formed in the cover plate 17, and having the bottom part engaging the toe plate 15. Thus the screws 20 are anchored against axial movement relative to the toe plate. Threadably mounted on each screw 20 is a nut 23 having a laterally inwardly extending projection 24 pivotally connected to the adjacent edge portion of the associated flange 16. The arrangement is such as to enable the toe irons to be moved bodily inwardly or outwardly or to be angularly adjusted by proper manipulation of the screws 20.

In the present instance the toe irons 14 are respectively connected to the outer edges of the flanges 16 by hinges 25 enabling the toe irons 14 to be swung laterally outwardly from their upright or boot clamping positions, shown in Fig-

ures 1 to 5 inclusive of the drawings. The toe irons 14 are located in their upright or boot clamping positions by suitable stop means associated with the front end portions of the toe irons. In detail the front ends of the toe irons are turned inwardly beyond the toe of the boot and are provided with depending projections 26. The projections 26 are adapted to rest against a suitable bearing plate 27 secured to the top surface of the ski in a position in advance of the toe plate 15. The arrangement is such that when the projections 26 engage the bearing plate 27 in the manner shown in Figure 4 of the drawings, the toe irons are located in their proper clamping positions with respect to the toe of the boot.

Inasmuch as the toe irons cooperate with one another to clamp the toe portion of a boot in position on the ski, it follows that some means must be provided for holding the toe irons against outward swinging movement from their respective boot clamping positions. In general this is accomplished herein by releasable means 28 adapted to resist outward swinging movement of the toe irons with a force sufficient to effectively hold the toe irons in their boot clamping positions during normal skiing maneuvers, but less than any force capable of straining either leg of the user beyond the breaking point. In detail a bracket 29 is secured to the ski 10 against the plate 27 by screws 30, and is provided with an upstanding flange 31 at the rear end thereof. The upstanding flange 31 is positioned forwardly beyond the toe irons and extends transversely of the ski at such an elevation to protect to some extent the toe portion of the boot clamped between the toe irons. A fitting 32 is secured to the rear face of the flange 31 between the front end portions of the toe irons 14 and is provided with a rearwardly extending post 33. The post 33 is located midway between the front end portions of the toe irons and has an enlargement 34 at the rear end formed with a lip 35. The enlargement 34 acts as a stop to limit forward movement of the boot relative to the binding, and the lip 35 is adapted to engage the top surface of the sole of the boot to prevent upward displacement of the toe of the boot relative to the binding.

The inwardly curved front end portion of each toe iron is provided with a rearwardly extending projection 40, and these projections are adapted to assume positions on laterally opposite sides of the post 33 when the toe irons are in their boot clamping positions shown in Figure 4 of the drawings. In the present instance the projections 40 are tied to the post 33 by a flexible, non-resilient linear member in the form of a cord 41. If desired, the cord 41 may first be tied to the post 33 and may then be wound around the projections 40 as well as the post 33 to secure the toe irons in their upright or boot clamping positions. The number of strands of the cord used to secure the toe irons in operative position is so determined with respect to the strength of the cord that the latter will release or break upon the application of an abnormal laterally outward force against one or both of the toe irons. The arrangement should be such that if for any reason the boot 12 is twisted in one direction or the other during skiing, the cord 41 will break before the strain on the leg of the user reaches the breaking point. It will, of course, be understood that the cord 41 may be wound with more turns connecting one toe iron to the post 33 than the number of turns connecting the other toe iron to the post, so that the latter toe iron will be released first. In fact

various different arrangements may be resorted to to suit the wishes of the user. As another example, the cord need not be wound around the center post 33 in which event it merely acts as a tie between the two toe irons. In any case the releasable means 28 acts as a safety device to minimize the danger of unduly straining or breaking the skier's legs. Attention may be called to the fact at this time that the number of turns or strands of the cord used to connect the toe irons together or to the center post 33 may be varied depending upon the strength of the legs of the particular user. This feature renders it possible to obtain the maximum safety for the particular user without altering the design or construction of the binding.

As shown in Figures 1 to 3 inclusive, the toe irons are provided with upstanding lugs 43 at the top edges thereof, and these lugs are slotted to receive a suitable toe strap not shown. This toe strap may be used in the field to temporarily secure the toe irons in their operative positions after the cord 41 has released the toe irons. However, the cord 41 may be very quickly replaced, and this practice is preferred from the standpoint of safety.

It follows from the foregoing that any condition encountered in skiing that tends to twist or shift one or both feet of the skier applies a lateral outward force on one or both the hinged toe irons, and if this force dangerously approaches any force capable of unduly straining the legs of the skier, the cord 41 breaks releasing the toe irons from the boot. This construction greatly reduces leg injuries, but does not entirely eliminate the possibilities of such injuries. For example, leg injury may result from a condition in skiing wherein forward motion of the skis is either retarded or stopped altogether with such suddenness that the momentum of the skier throws the body forwardly, and of course, tends to lift the heel portions of the boots off the skis. When considering that most ski bindings have means for holding the heel portions of the boots down against the skis with a force of sufficient magnitude to enable the skier to lean far forward over the front portions of the skis without losing balance, it will be understood that any sudden retardation of the forward motion of the skis may place a strain on the legs of the skier sufficient to break or fracture the same. This invention overcomes any such danger without interfering with the normal operation of the binding by providing means for releasing the heel portions of the boots from the respective skis in response to the application of an abnormal lifting force on the heel portions.

With the above in view, reference is again made to the drawings, wherein one type of popular heel hold-down mechanism is shown. This mechanism comprises a flexible cable 45 and a releasable clamp 46 secured to the ski well in advance of the boot. In general the clamp 46 has a base plate 47 slidable on the ski and having a plurality of transverse ribs spaced from each other lengthwise of the ski. The adjacent ribs cooperate to form recesses 48 for selectively receiving the cable 45. The upper ends of the recesses are closed to prevent accidental disengagement of the cable by a clip 49 having the rear end fashioned to snap over the corresponding end of the base plate 47 and having the front end pivoted to the plate 47. The plate 47 is connected at its front end to the lever 50 by links 52, and the lever in turn is pivoted to a

5 bracket 51 suitably secured to the ski in advance of the plate 47. The construction is such that the cable 45 is selectively loosened and tightened by swinging the lever in opposite directions in accordance with orthodox practice.

10 The cable 45 is looped intermediate the ends and the looped portion is selectively engaged in the recesses 48 to vary the effective length of the cable, or as will be presently noted, to vary the force tending to hold the heel portion of the boot down against the ski. The free ends of the cable 45 are connected by a coil spring 53 and the latter is adapted to seat in a groove formed in the heel of the boot. The tension of the spring, and accordingly, the force tending to clamp the heel of the boot on the ski depends on the effective length of the cable which in turn is varied by anchoring the cable in different recesses 48 provided on the clip. Also, in order to increase the downward force component applied to the heel of the boot by the cable, suitable brackets 54 are attached to opposite side edges of the ski in advance of the heel of the boot for respectively engaging the opposite side portions of the looped cable. Thus the boot is not only firmly held downwardly on the ski, but is also held against fore and aft movement relative to the ski.

15 Although the spring 53 acts to yieldably clamp the heel of the boot against the ski, nevertheless, the tension of the spring is usually such that only a very limited lift of the heel is permitted so that the skier may lean far forward without releasing the bindings from the boots. 20 If for some reason, while in the above position, forward motion of the skis is suddenly retarded, a strain may be applied to the skier's legs sufficient to fracture one or both legs.

25 In accordance with this invention, however, the cable is released from the heel of the boot in the event the lifting force applied to the heel of the boot approaches a force that may unduly strain the legs of the skier. One form of cable release is shown in Figures 6, 7 and 8 of the drawings. This release comprises a flexible strap 60 and a clamp 61. The clamp 61 has a plate 62 secured to the top of the ski rearwardly of the plate 13, and has an upstanding threaded post 63 on the plate for threadably engaging a 30 thumb nut 64. The nut 64 engages a clamping part 65 apertured to receive the post 63 and having depending flanges F at opposite side edges adapted to rest on the plate 62.

35 The strap 60 is looped intermediate the ends around the spring 53 and the free end portions of the strap extend rearwardly between the plate 62 and the part 65. The free end portions of the strap are formed with registering openings O spaced from each other longitudinally of the strap for selectively receiving the threaded post 63. Also opposite sides of the strap are fastened together by a fastener element 66 to provide a loop of sufficient size to accommodate the spring 53.

40 It follows from the above that the strap applies a force in a downward and rearward direction on the spring 53 after the heel of the boot is raised an amount depending upon the length of the strap 60. The amount of downward force required to release the spring 53 from the heel of the boot depends on the tension of the spring or upon the adjustment of the cable length and in any case is less than any force that may unduly strain the legs of the skier.

45 The embodiment of the invention shown in

Figures 9 to 12 inclusive differs from the one previously described in that the strap 60 is adjustably clamped on the ski without the aid of holes in the strap. In detail a plate 61' is secured to the ski by suitable fastening means, and a bracket 62' is fixed to the plate by the same fastening means. The bracket 62' has a recess 63' formed therein for receiving the free end portions of the strap 60 in superposed relationship and opposite sides of the recess are formed with vertical grooves 64'. Suitable clamping plates 65' and 66' are positioned in the recess 63'; and are formed with laterally outwardly projecting tongues 67 at opposite side edges for respectively engaging in the grooves 64'.

In use the bottom plate 68' is positioned between the free ends of the strap 60 and the top plate 69' abuts the top surface of the uppermost end of the strap, as clearly shown in Figure 9 of the drawings. The plates 65' and 66' are frictionally clamped to the strap 60 by a thumb screw 67' threadably engaging in a threaded bore formed in the top of the bracket 62' and engageable with the top plate 69'. Thus the effective length of the strap between the bracket and spring 53 may be infinitely varied between limits by merely manipulating the thumb screw 67'.

The loop portion at the front end of the strap is formed by spaced plates 70 and 71 respectively engageable with opposite sides of the strap adjacent the loop and secured together by clamping screws 72. The clamping screws are spaced laterally beyond opposite side edges of the strap, and as a result, the strap need not be apertured to receive the screws. As a result the strap may be imperforate and this is desirable where maximum strength is required.

The modification shown in Figures 13 to 15 inclusive differs from either of the above constructions in that one end of the strap 60 is secured to the ski by a plate 73 and screws 74. The other end portion of the strap is clamped to the plate 73 by a clamping lever 75 pivoted to a bracket 76 for swinging movement in a vertical plane and having a serrated cam face 77 positioned to engage the upper or free end of the strap in the horizontal position of the lever shown in Figure 13 of the drawings. The lever 75 is held in its clamped position with respect to the belt by a leaf spring 78 pivoted at the front end on the bracket 76 and having the rear end engageable with the corresponding end of the lever 75 adjacent the finger engaging hole 79 in the lever. The construction is such that when it is desired to release the free end of the strap for adjustment or other purposes, the operator merely swings the spring 78 laterally out of engagement with the lever 75 and swings the latter upwardly to release the strap.

The front end of the strap is held in loop fashion by a fitting 80 comprising laterally spaced triangular plates 81 respectively connected at the corners by pins 82, 83 and 84. The pin 84

extends through the loop and the pins 82 and 83 are respectively positioned at opposite sides of the strap rearwardly of the loop. Thus one end of the strap may be adjusted relative to the other end portion upon releasing the clamping lever 75.

In each of the several embodiments noted above, the strap is provided with a definite loop at the front end for receiving the spring 53 at the rear of the cable. This loop acts to hold the forward end of the strap in an elevated position shown in Figures 7, 9 and 13 of the drawings, and locate the spring loop 53 in a position which facilitates placing the heel of the boot into the binding. Also each of the several types of strap assemblies employed function to release the heel of the boot in response to the application of an abnormal upward force on the heel portion of the boot. This feature, together with the releasable toe irons previously described, greatly increases the safety of the binding without impairing its performance.

What I claim as my invention is:

1. A ski binding comprising means for positioning a boot on a ski, means for yieldably clamping the heel portion of the boot on the ski including a coil spring having the opposite end portions respectively anchored to opposite sides of the ski forwardly of the heel portion on the boot and having an intermediate portion adapted to be looped around the back of the heel portion of the boot, a flexible non-resilient strap having the end portions folded to overlie one another and provide a loop through which the spring extends, a pin fixed on the ski in spaced relation to the position normally occupied by the heel of the boot and projecting upwardly from the ski through aligned openings in the free end portions of said strap and a clamping element mounted on the pin and cooperating with said pin to secure the free end portions of the strap in place.

2. The ski binding set forth in claim 1 in which the free ends of the strap are provided with a plurality of longitudinally spaced aligned openings selectively engageable with the pin to vary the effective length of said strap.
